UNITED STATES PATENT OFFICE.

POWHATAN ROBINSON, OF NEW YORK, N. Y., ASSIGNOR TO NEW YORK SPORTING GOODS COMPANY, OF NEW YORK, N. Y., A CORPORATION OF NEW YORK.

DESIGN FOR A TENT.

49,446.

Specification for Design.

Patented July 25, 1916.

Application filed March 1, 1916. Serial No. 81,559. Term of patent 7 years.

To all whom it may concern:

Be it known that I, Powhatan Robinson, a citizen of the United States of America, residing at New York city, county and State of New York, have invented a new, original, and ornamental Design for a Tent, of which the following is a specification, reference being had to the accompanying drawing, forming part hereof, in which—

Copies of this patent may be obtained for five cents each, by addressing the "Commissioner of Patents, Washington, D. C."

I claim:

The ornamental design for a tent as shown.

Signed at New York city, New York, this 28 day of February, 1916.

POWHATAN ROBINSON.

Witnesses:

MAURICE BLOCK,
EDWARD A. JARVIS.
